UNITED STATES PATENT OFFICE.

RICHARD N. B. KIRKHAM, OF WESTFIELD, ILLINOIS.

DESIGN FOR A BADGE.

SPECIFICATION forming part of Design No. 37,021, dated July 5, 1904.

Application filed May 11, 1904. Serial No. 207,499. Term of patent 3½ years.

To all whom it may concern:

Be it known that I, RICHARD N. B. KIRKHAM, a citizen of the United States, residing at Westfield, in the county of Clark and State 5 of Illinois, have invented a new, original, and ornamental Design for a Badge, as disclosed in the accompanying drawing, which illustrates the badge in perspective.

What I claim as new, and desire to secure by Letters Patent, is—

The ornamental design for a badge, as shown.

RICHARD N. B. KIRKHAM.
